UNITED STATES PATENT OFFICE

WILLIAM C. FLOYD, OF HAWKINSVILLE, GEORGIA

AUTOMATIC PISTOL

Application filed December 12, 1932. Serial No. 646,889.

The device forming the subject matter of this application is an automatic pistol, and one object of the invention is to improve the mechanism for cocking and releasing the hammer. Another object of the invention is to improve the construction of the slidable breech block, by which the hammer is cocked, and by which other operations are carried out. Another object of the invention is to 10 improve the safety mechanism.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and 20 claimed, it being understood that changes in the precise embodiment of the invention herein disclosed, may be made within the scope of what is claimed, without departing from the spirit of the invention.

In the accompanying drawings:

Fig. 1 shows in longitudinal section, a pistol constructed in accordance with the invention, the parts being in the positions which they will assume when the pistol is about to 30 be discharged, it being assumed that the shooter has not yet gripped the stock;

Fig. 2 is a view similar to Fig. 1, but showing the pistol at the instant of firing, pressure being still exerted on the trigger and on the 35 grip;

Fig. 3 is a view similar to Fig. 1, but showing the breech block retracted;

Fig. 4 is a top plan view of the head of the breech block;

Fig. 5 is a bottom plan of the head of the breech block;

Fig. 6 is a longitudinal section showing a portion of the frame and the barrel;

Fig. 7 is a section on the line 7—7 of Fig. 3;

Fig. 8 is a section on the line 8—8 of Fig. 1;

Fig. 9 is a section on the line 9—9 of Fig. 1;

Fig. 10 is a plan of the breech block, with some parts omitted;

Fig. 11 is a section on the line 11—11 of

50 Fig. 1;

Fig. 12 is an elevation showing modification.

The pistol which forms the subject matter of this application has some of the features made known to the art in my Patent 1,886,201, 55 granted on July 5, 1932, and the present specification, therefore, may be shortened and condensed accordingly.

The frame of the pistol is marked by the numeral 1, and includes a grip 2 and a trigger guard 3 at the forward end of the frame. The barrel 4 is fixed to the frame 1 and may be threaded therein.

Figure 1 shows that a magazine 5 is slidably and removably mounted in the grip 2. 65 The magazine 5 has a foot plate 6. A latch 7 is slidable in the grip 2 and engages a projection on the magazine 5, to hold the magazine in place. A spring-pressed thrust member 8 is slidable in the grip 2 and is held in place for limited movement, by a pin 9 in the grip. The member 8 bears against the foot plate 6 of the magazine 5, and starts the magazine for removal, when the latch 7 is operated to permit such a step. A follower 70 75 10 in the magazine 5 raises the cartridges, the follower being actuated by a compression spring 11 in the magazine.

Figures 6 and 3 show that there is a compartment 12 in the upper part of the frame 1. 80 The compartment 12 extends entirely through the frame from side to side, the compartment terminating at its forward end at the rear end of the barrel 4, and the rear end of the compartment being determined by a back piece 14 that forms part of the frame 1. There is a hole 15 in the back piece 14. Figures 6 and 7 show that there are longitudinal guide grooves 16 in the frame 1, at the outer sides of the compartment 12. It appears in Fig. 6 85 that there is an upstanding shell-throwing pin 17 on the frame 1, within the compartment 12, just back of the upper end of the magazine 5. Figures 3, 6 and 7 may be relied upon to show that the frame 1 carries an abutment 18, located about midway between the ends 90 of the compartment 12, and extending across the compartment from top to bottom. The abutment 18 has an opening 19.

A breech block 20 is slidably mounted in 100

the frame 1, and is shown partially completed in Fig. 10. The breech block 20 is a composite structure. It includes the head 21 of Figs. 4 and 5, which is mounted to slide, parallel to the axis of the barrel 4, in the compartment 12 of the frame 1. Regarding the foregoing statement that the head 21 of the breech block 20 slides parallel to the axis of the barrel 4, the reader should not be confused by the dotted line showing of the head 21 of the breech block, in Fig. 6. That showing has to do with the assembly of the breech block and associated parts, and may be disregarded at this stage of the description. The forward side portion of the head 21 of the breech block 20 carries a pivotally mounted, spring-pressed extractor 22.

The head 21 of the breech block 20 has rearwardly extended parallel arms 26, which straddle the abutment 18, as Fig. 7 will show. In the bottom of the head 21 of the breech block 20 (Fig. 5) there is a first longitudinal groove 23, for the reception of the frame-carried shell-throwing pin 17 of Fig. 6. In the edge of the head 21 of the breech block 20 there is a notch 29, having no function in the operation of the pistol, considered as a firearm, but facilitating the assembly of the breech block 20, as will be pointed out hereinafter. The notch 29 opens into the guide groove 23. In the bottom of the head 21 of the breech block 20, a second groove (Fig. 5) is formed, the said groove 24 being parallel to the groove 23. The groove 24 does not extend entirely through the head 21 of the breech block, and thus there is formed in the breech block, at the end of the groove 24, a shoulder 25 which, as shown in Fig. 3, cooperates with parts to be described hereinafter.

The breech block 20 (Fig. 10) comprises a back piece 27, carrying a knob 28 of any desired construction, whereby the breech block 20 can be retracted, to cock the piece by hand. The forwardly-extended arms 30 of the back piece 27 (Fig. 7) slide in the guide grooves 16 of the frame 1. The forwardly-extended arms 30 of the back piece 27 overlap the rearwardly-extended, recessed arms 26 of the head 21 of the breech block, the arms 26 and 30 being held together by oppositely disposed securing elements 31 (Fig. 7), such as screws.

A cocking block 32 (Figs. 3 and 7) is disposed to the rear of the abutment member 18 of the frame 1, between the arms 30 of the back piece 27 of the breech block 20, and is located at the rear ends of the arms 26 of the head 21 of the breech block. Securing elements 33, such as screws, attach the cocking block 32 to the arms 30, and make the cocking block a part of the breech block 20.

A sleeve 34 is engaged at its rear end with the cocking block 32 and slides in the opening 19 of the abutment 18, the sleeve ex-

tending through the abutment, and into a large bore 35 in the head 21 of the breech block 20. The head 21 has a smaller bore 36, which extends forwardly from the large bore 35. 70

A firing pin 37 slides in the cocking block 32 and in the sleeve 34. The firing pin is slidably mounted, also, in the small bore 36 of the head 21 of the breech block. The firing pin 37 is retracted with respect to the breech block, through the instrumentality of a small compression spring 38 in the bore 36, and shown, for example, in Fig. 3. The firing pin 37 has a disk-like head 39, which engages the forward end of the sleeve 34. A compression spring 40 surrounds the sleeve 34, the forward end of the said spring engaging the head 21 of the breech block 20, within the bore 35, and the rear end of the spring engaging the abutment 18 of the breech block. The movement of the firing pin 37 is limited by a cross pin 41, shown in Fig. 7, and extended through a notch in the firing pin. 85

The manner of assembling the breech block 20 may now be taken up, in connection with Figs. 6 and 7.

The small spring 38 is placed in a small bore 36 of the head 21 of the breech block, and the heavier spring 40 is placed in the large bore 35 of the part 21. The head 21, in the dotted position of Fig. 6, is introduced endwise into the compartment 12 of the frame 1, and is pushed inwardly to place, the pin 17 of Fig. 6 entering the groove 23 of Fig. 5 by way of the notch 29, the arms 26 of the head 21 straddling the abutment 18. The cocking block 32 is not yet in place, and, therefore, the sleeve 34 and the firing pin 37 may be pushed forwardly to place, through the hole 15 of the back piece 14. The holding element 41 for the firing pin 37 is mounted in the head 21 of the breech block. The cocking block 32 is placed in the position of Fig. 7, against the rear ends of the arms 26 of the head 21. The arms 30 of the back piece 27 are slid forwardly into the grooves 16 (Fig. 6) of the frame 1, and lie outside of the arms 26 of the head 21. The securing elements 33 are inserted, to hold the cocking block 32 on the arms 30 of the back piece 27. The arms 30 of the back piece 27 are joined to the arms 26 of the head 21, by the securing elements 31. The breech block 20 now is assembled and in place. 110

A trigger 42 is disposed within the trigger guard 3, and is pivoted at 43 to the frame 1. The lower end of the trigger 42 is swung forwardly by a compression spring 44 (Fig. 2), housed within the frame 1 and engaging the upper end of the trigger. 120

A loop-shaped link 45 (Fig. 11) extends around the magazine 5, the link projecting into a large chamber 46 in the frame 1, through a hole 47 that leads from the trigger guard 3 to the said chamber. The forward 125

end of the link 45 is pivoted at 48 to the trigger 42.

The rear end of the link 45 is pivoted at 49 to a sear 50, in the form of a bell crank lever, disposed in the chamber 46, and fulcrumed at 51 on the frame 1. The movement of the sear 50 is limited by a pin 52, carried by the frame 1, and extended through an elongated slot 53 in the sear. On its rear 10 end, the sear 50 has an upwardly extended finger 54.

The finger 54 on the sear 50 is adapted to cooperate with a shoulder 55 on a hammer 56 that is pivoted at 57 on the frame 1, the hammer extending upwardly through an opening 85 in the frame and into the compartment 12, to actuate the firing pin 37 (Fig. 2). The upper part of the hammer 56 lies in the path of the cocking block 32 20 (Fig. 3) which forms part of the slidable breech block 20.

The spring means for operating the hammer 56 may be of any desired form. In the present embodiment of the invention, a plunger 58 is pivoted at 59 to the hammer 56 and slides in an abutment 60 carried by the frame 1, a compression spring 61 on the plunger being interposed between the abutment 60 and a shoulder on the plunger. The numeral 62 25 designates an angular sear operator, disposed mostly in the chamber 46, and mounted for swinging movement on a pivot element 63 carried by the frame 1. One end of the sear operator 62 extends upwardly through a slot 30 64 in the frame 1, into the path of the shoulder 25 which exists in the head 21 of the breech block 20, at the forward end of the groove 24, the said groove receiving the upper forward end of the sear operator 62. The 35 rear lower end of the sear operator 62 bears on the finger 54 of the sear 50, under the impulse of a compression spring 65 which is interposed between the frame 1 and the rear 40 end of the sear operator 62.

45 A lever 66, actuated when the grip 2 is seized, is fulcrumed at 67 on the grip, the upper end of the grip lever 66 being pivoted at 68 to a safety slide 69, which, as shown in Fig. 9, has a slot 70 for a securing element 50 71, by which the safety slide is movably connected to the frame 1. The safety slide 69 is pushed backwardly, and the grip lever 66 is 55 swung rearwardly, by a compression spring 72, interposed between the forward end of the safety slide and a part of the frame 1.

In the bottom of the forward end of the safety slide 69 there is a recess 73, shown in Figs. 1, 2 and 3. The safety slide 69 is provided with a lateral projection 74 (Fig. 9) which 60 extends above the finger 54 of the sear 50, when the safety slide is retracted, and when the grip lever 66 is swung outwardly by the action of the spring 72, as shown in Fig. 1.

A latch 75 (Figs. 1, 2 and 3) for the safety 65 slide 69 is provided, and is fulcrumed at 76,

intermediate its ends on the frame 1. A compression spring 77 is interposed between the lower part of the latch 75 and a part of the frame 1. The tendency of the spring 77 is to swing the hind end of the latch 75 up into the recess 73 of the safety slide 69, and stop the forward movement of the safety slide, but, ordinarily, the latch 75 does not work in that way, because, when the magazine 5 is in place, the magazine engages the forward end of the latch 75 and tilts the latch until the back end of it is out of the recess 73, and out of the path of the slide 69, in its forward movement, as shown, for instance, in Fig. 2.

It is disclosed in Fig. 8 that an indicator lever 78 is disposed alongside of the hammer 56, an indicator 79, in the form of a button, being secured to the rear end of the lever 78, the indicator extending outwardly through a hole 80 in the side of the frame 1. The indicator lever 78 is fulcrumed at 81, at its forward end, on the frame 1, for swinging movement crosswise of the pistol. A compression spring 82 is mounted between the frame 1 and the lever 78, and tends to swing the lever inwardly against the side of the hammer 56.

Considering Fig. 1, the operator seizes the grip 2 and swings the grip lever 66 forwardly on its fulcrum 67, the safety slide 69 being carried forwardly until the lateral projection 74 (Fig. 9) on the safety slide is clear of the finger 54 of the sear 50. This sets the sear 50 free, so that the trigger 42 can be pulled. When the trigger 42 is pulled, the link 45 is carried backwardly, the bell crank sear 50 is tilted on its fulcrum 51, and the finger 54 of the sear is disengaged from the shoulder 55 on the hammer 56, the upper end of the hammer swinging forwardly under the impulse of the spring-actuated plunger 58, the hammer 95 striking the firing pin 37 and moving the firing pin forwardly, the spring 38 being compressed, and the firing pin 37 exploding the cartridge shown in place in the shell chamber of the barrel 4 in Fig. 2. As the finger 100 54 of the sear 50 rises out of engagement with the shoulder 55 on the hammer 56, when the trigger 42 is pulled, the finger engages the depending rear end of the sear operator 62, and swings the rear end of the sear operator upwardly, the spring 65 being compressed as the sear operator 62 swings on its fulcrum 63.

When the shell in the barrel 4 explodes, the recoil carries the entire breech block 20 rearwardly, and the extractor 22 withdraws 110 the exploded shell, brings the shell into contact with the projection or frame pin 17 of Fig. 6, and ejects the shell through the side of the forward portion of the compartment 12, the forward portion of the compartment 12 then being open, because the breech block has been carried backwardly to the position of Fig. 3, the return spring 40 for the breech block having been compressed, and the back 115 part of the head 21 of the breech block com-

ing into engagement with the abutment 18 on the frame 1.

As the breech block 20 moves rearwardly, the cocking block 32 engages the hammer 56 and swings the hammer back to cocked position, as in Fig. 3. The trigger 42 having been released, the spring 65 swings the rear end of the sear operator 62 downwardly and tilts the sear 50 downwardly at its rear end, 10 the finger 54 being disposed in the path of the shoulder 55 on the hammer 56, this operation taking place during the time that the breech block 20 is moving rearwardly. When the breech block 20 moves rearwardly, the shoulder 25 on the head 21 of the breech block engages the upper end of the sear operator 62, and holds the back end of the sear operator from swinging upwardly with respect to the finger 54 of the sear 50, it being thus impossible to pull the trigger 42 whilst the pistol is open.

Whilst the breech block 20 is retracted, as in Fig. 3, the spring 11 (Fig. 1) acts on the follower 10 to raise a new shell (Fig. 3) out 25 of the magazine 5, into the path of the head 21 of the breech block, so that the shell will be advanced into the shell chamber of the barrel 4, when the breech block moves forwardly.

The breech block 21 moves forwardly to 30 the position of Fig. 1, responsive to the spring 40, shown compressed in Fig. 3. The cocking block 32 moves out of engagement with the hammer 56, and the hammer swings forwardly under the actuation of the spring-pressed 35 plunger 58, from the position of Fig. 3 to the position of Fig. 1, the shoulder 55 on the hammer engaging the finger 54 of the sear 50, the hammer being held cocked. The pistol then is in condition to be fired again. The 40 forward movement of the breech block 20 carries the new shell from the position of Fig. 3, into the shell chamber of the barrel 4, as in Fig. 1.

When the operator releases his hold on the 45 grip 2, he frees the grip lever 66, and the grip lever swings backwardly on its fulcrum 67, under the actuation of the safety slide 69, which, in its turn, is carried backwardly by the spring 72. As the safety slide 69 is carried 50 backwardly by the spring 72, the lateral projection or detent 74 (Fig. 9) on the slide 69 is carried above the finger 54 on the sear 50. The sear 50, therefore, cannot be disengaged from the shoulder 55 of the hammer 56, and the hammer is locked in cocked position, until such time as the operator seizes 55 the grip 2, swings the grip lever 66 forwardly, and advances the safety slide 69 to a position in which the detent 74 of the slide 60 no longer is above and engaged with the finger 54 of the sear 50.

Referring to Fig. 8 in connection with Fig. 1, it will be clear that as the hammer 56 moves rearwardly to cocked position, it swings the 65 indicator lever 78 outwardly at its rear end,

thereby causing the indicator 79 to stick out through the hole 80 in the frame 1, and the operator, by sliding his hand over the side of the pistol, is admonished that the piece is cocked. When, however, the hammer 56 swings forwardly far enough, the spring 82 of Fig. 8 swings the indicator lever 78 inwardly, thereby retracting the indicator 79 and tipping off the operator to the fact that the pistol is not cocked.

Noting Fig. 1, for instance, when the magazine 5 is pulled out of the grip 2, the magazine no longer engages the latch 75 and holds the rear end of the latch below and clear of the safety slide 69. With the magazine 5 removed, the back end of the latch 75 is swung upwardly by the spring 77, into the recess 73 of the safety slide 69. Therefore, although the operator may take hold of the grip 2 and press on the grip lever 66, he cannot advance the safety slide 69 and move the detent 74 on the slide (Figs. 9 and 1) from above the finger 54 of the sear 50. The result is that the pistol cannot be discharged when the magazine 5 is withdrawn.

The sights 83 are carried by the barrel 4 and by the rear part of the frame, and since the barrel is fixed to the frame, both sights are fixed also. This construction has manifest advantages over a construction in which one of the sights is carried by a movably mounted barrel.

The device may be embodied in a pistol of the old-fashioned grip construction, as shown in Fig. 12. In that figure, parts hereinbefore described have been designated by numerals hereinbefore used, with the suffix "a". In this form of the invention, the magazine is not in the grip 2a, but is in a magazine holder 84, forming part of the frame, but located in advance of the trigger guard 3a. The inspection plate 86a is held in place by securing elements that form supports for many of the working parts of the pistol, and may be taken off readily, carrying such working parts with it. The same is true of the inspection plate 86 of Figs. 8 and 9.

Having thus described the invention, what is claimed is:

1. A pistol comprising a frame, a hammer movably mounted on the frame, a barrel fixed on the frame, a breech block mounted to reciprocate on the frame, the breech block forming an abutment for a cartridge in the barrel, the breech block being rearwardly movable, responsive to the recoil of an exploding cartridge, to move the breech block rearwardly, the breech block engaging the hammer, as the breech block moves rearwardly, thereby to cock the hammer, spring means for advancing the breech block, firing means carried by the breech block and located between the hammer and the barrel, a trigger movably mounted upon the frame, a sear in the form of a bell crank lever fulcrumed

on the frame, one end of the sear engaging the hammer, to hold the hammer cocked, a link pivoted to the trigger and to the opposite end of the bell crank sear, and a sear operator movably mounted on the frame and engaging the sear, to cause the sear to engage the hammer and hold the hammer cocked, the sear operator extending into the path of the breech block, whereby, when the breech block moves rearwardly, to cock the hammer, the breech block will act, through the instrumentality of the sear operator, to hold the sear engaged with the hammer.

2. The pistol of claim 1, in combination with a supply magazine for the barrel, the magazine being removably mounted in the frame, between the trigger and the sear, the link extending transversely of the magazine, and being offset to clear the magazine.

3. A pistol comprising a frame, a hammer movably mounted on the frame, a barrel fixed upon the frame, a breech block mounted to reciprocate on the frame, the breech block forming an abutment for a cartridge in the barrel, the breech block being rearwardly movable, responsive to the recoil of an exploding cartridge, to move the breech block rearwardly, the breech block engaging the hammer, as the breech block moves rearwardly, thereby to cock the hammer, spring means for advancing the breech block, firing means carried by the breech block and located between the hammer and the barrel, a trigger movably mounted upon the frame, sear means cooperating with the hammer, to hold the hammer cocked, the sear means being operatively associated with the trigger, a sear operator movably mounted on the frame and engaging the sear means, to cause the sear means to engage the hammer and hold the hammer cocked, the sear operator extending into the path of the breech block, whereby, when the breech block moves rearwardly, to cock the hammer, the breech block will act, through the instrumentality of the sear operator, to hold the sear engaged with the hammer.

4. A pistol comprising a frame, a hammer movably mounted on the frame, a barrel fixed upon the frame, a breech block mounted to reciprocate on the frame, the breech block forming an abutment for a cartridge in the barrel, the breech block being rearwardly movable, responsive to the recoil of an exploding cartridge, to move the breech block rearwardly, the breech block engaging the hammer, as the breech block moves rearwardly, thereby to cock the hammer, spring means for advancing the breech block, firing means carried by the breech block and located between the hammer and the barrel, a trigger movably mounted on the frame, sear means associated with the trigger and engaging the hammer, to hold the hammer cocked, a sear operator movably mounted on

the frame and engaging the sear means, to cause the sear means to engage the hammer and hold the hammer cocked, the sear operator extending into the path of the breech block, whereby, when the breech block moves rearwardly, to cock the hammer, the breech block will act, through the instrumentality of the sear operator, to hold the sear means engaged with the hammer, a safety slide mounted to reciprocate on the frame, spring means for retracting the safety slide to cause the safety slide to cooperate with the sear means and hold the sear means engaged with the hammer, and mechanism for advancing the safety slide to disengage it from the sear means, said mechanism being a grip lever pivoted at its upper end to the safety slide, and pivoted at its lower end to the grip portion of the frame.

5. A pistol constructed as set forth in claim 4, in combination with a magazine removably mounted in the frame, a latch movably mounted on the frame and held out of engagement with the safety slide, by engagement with the magazine, when the magazine is in place, and means for operating the latch, when the magazine is removed, to cause the latch to engage the safety slide and hold the safety slide in engagement with the sear means, when the safety slide is retracted.

6. A pistol comprising a frame, a barrel mounted on the frame, an abutment mounted on the frame, a breech block movable on the frame, toward and from the barrel, the breech block comprising forward and rear parts having overlapped, oppositely-extended arms, which are detachably secured together, the arms of the forward part of the breech block straddling the abutment, and the arms of the rear part of the breech block being slidably mounted on the frame, a compression spring interposed between the abutment and the forward part of the breech block, and a firing pin slidable in the breech block, the rear part of the frame having an opening through which the firing pin can be inserted into the breech block.

7. A pistol constructed as set forth in claim 6, in combination with a hammer movably mounted on the frame and cooperating with the firing pin, and a cocking block cooperating with the hammer, the cocking block being mounted between the arms of the rear part of the breech block.

In testimony that I claim the foregoing as my own, I have hereto affixed my signature.

WILLIAM C. FLOYD.
